UNITED STATES PATENT OFFICE.

JOHN M. RUSBY, OF PHILADELPHIA, PENNSYLVANIA, ASSIGNOR TO THE UNITED GAS IMPROVEMENT COMPANY, OF PHILADELPHIA, PENNSYLVANIA, A CORPORATION OF PENNSYLVANIA.

WATER-GAS APPARATUS.

No. 857,760.

Specification of Letters Patent.

Patented June 25, 1907.

Application filed January 31, 1907. Serial No. 354,981.

To all whom it may concern:

Be it known that I, JOHN M. RUSBY, a citizen of the United States, residing at Philadelphia, in the county of Philadelphia and State of Pennsylvania, have invented certain new and useful Improvements in Water-Gas Apparatus, of which the following is a specification.

The principal object of the present invention is to provide means for definitely controlling the quantity and quality of the production of gas. By these means the attendant is enabled to introduce a definite volume of air during the intervals of each blow regardless of fire and other conditions in the generating apparatus, so that during the successive "runs," or gas producing periods, the apparatus will be in any definitely desired condition of heat and thus the introduction of oil and steam or the gas making process, as a whole, is effected under such conditions that the various steps in the gas making process which are productive of the best results may be accomplished and the apparatus worked most economically and efficiently.

To these and other ends hereinafter set forth, the invention comprises the improvements to be presently described and finally claimed.

30 In the drawings, Figure 1, is a top or plan view of portions of a water gas set or apparatus embodying features of the invention, and Fig. 2, is an elevational view of the same.

Referring to the drawings 1, is a generator, 35 2, a carbureter, 3, a superheater, and 4, the seal of the eduction end of the apparatus. These are the ordinary and well understood parts of a water gas apparatus and they are appropriately interconnected and provided 40 with oil and steam connections which are too well understood to require description or illustration.

45 5, is an air-pipe from which air is conducted to the various parts of the apparatus by means of branch pipes 6, 7, and 8. There are valves for regulating the supply of air, and they are indicated at 9.

50 10, is an ajutage, sometimes designated a "Venturi" tube, and it is interposed in the pipes or branches through which air is supplied to the parts of the apparatus. This ajutage affords means for indicating the volume of air per second or other unit of time passing through it by reason of the different

pressures which simultaneously exist within, 55 respectively, its most contracted area or throat, and its larger area on each side of the throat and since this indication is continuous, it enables the attendant at a glance to know the volume of air passing to the apparatus. 60

In order to operate water gas apparatus most economically and efficiently, it is desirable to perform each of the steps of the process in the manner that has been ascertained to be most efficient. For instance, at 65 each blow a predetermined volume of air should be introduced, otherwise the apparatus will not be properly heated for the reception of a predetermined quantity of oil and steam. The condition of the fire will effect 70 the volume of air passing through it under a given pressure, in some cases permitting too large a volume of air to pass with the result that fuel is unnecessarily consumed and the apparatus probably too highly heated, and 75 in other cases, precluding the passage of sufficient air in which case the requisite heat is not attained for carrying out the gas making process in accordance with the pre-arranged plan. The volume of gas made is substantially proportional to the quantity of air introduced provided the proper quantity of steam and oil are supplied. From the foregoing the importance of the admission of a pre-determined volume of air is apparent. 80 11, is a pressure gage, shown as of the well known "U" shaped form provided with peccocks 12, and with valves 13, and it is arranged where the attendant can readily see it. For example, these various pressure 85 gages are arranged above the operating floor 14. 15, is a scale by which the gages can be read and it may be arranged so as to be slidably mounted in order to adjust its position in respect to the fluid level in the U-shaped 90 gage. The arms of the gage are connected by tubes or pipes 16 and 17, with appropriate parts of the ajutage.

In operating the apparatus during the blow, the attendant knows in advance the volume 100 of air that is to be introduced and he can at all times accomplish this by reference to the pressure gages. If they indicate that too much or too little air is passing to the apparatus, the attendant accordingly regulates 105 the supply of air by the valves 9. In this way the pre-determined volume of air is introduced regardless of fire and other conditions.

so that the next steps of the gas making process may be carried on in a pre-determined manner; thus the operation, as a whole, may be carried on in that manner which is known 5 to be the best instead of being carried on largely according to the judgment of the attendant who, for instance, in the matter of the introduction of air usually opens the air valves 9 to a certain extent and then pre- 10 sumes that the requisite volume of air will reach the apparatus, whereas in fact the condition of the fire and other conditions will materially change the volume of air introduced. The introduction of different vol- 15 umes of air produces different results and in consequence if the later steps of the process are carried on according to pre-determined rule they will not be uniformly effective and economical.

What I claim as new is:

Means for definitely controlling the quantity and quality of the production of gas, which means comprise the gas generating apparatus and its regulatable air supply connections and an ajutage interposed in said connections and provided with a pressure gage, whereby the attendant is enabled to introduce a definite volume of air during the interval of each blow regardless of fire and other conditions in the apparatus, substan- 20 25 30 tially as described.

In testimony whereof I have hereunto signed my name.

JOHN M. RUSBY.
